UNITED STATES PATENT OFFICE.

JAMES M. TROTTER, OF ALMA, CALIFORNIA.

MOTOR FOR VEHICLES.

SPECIFICATION forming part of Letters Patent No. 592,674, dated October 26, 1897.

Application filed November 9, 1896. Serial No. 611,528. (No model.)

To all whom it may concern:

Be it known that I, JAMES M. TROTTER, of Alma, in the county of Santa Clara and State of California, have invented a new and Improved Motor for Vehicles, of which the following is a full, clear, and exact description.

My invention relates to that class of motors used for the purpose of auxiliary propulsion; and the object of the invention is to provide a motor of the class specified which is simple and durable in construction, arranged to form a brake and to accumulate power during the travel of a drawn or propelled car, wagon, or other vehicle on a downgrade, and to utilize this power for propelling purposes when going uphill, &c.

The invention consists of certain parts and details and combinations of the same, as will be fully described hereinafter and then pointed out in the claims.

Reference is to be had to the accompanying drawings, forming a part of this specification, in which similar characters of reference indicate corresponding parts in all the figures.

Figure 1 is a sectional side elevation of the improvement. Fig. 2 is a plan view of the same with parts broken out, and Fig. 3 is a side elevation of a modified form of air-motor.

On the rear axle A' of the vehicle A of any approved construction are secured the friction-disks B and the gear-wheels C, of which the former are adapted to be engaged at their peripheries by friction-disks D, secured on a transversely-extending shaft E, mounted to turn in suitable bearings arranged in levers F, fulcrumed at F', and carrying a second shaft G, on which are fastened the pinions H, adapted to be thrown in mesh with the gear-wheels C. The friction-disks D are arranged on the upper end of the levers F and the pinions H on the lower end thereof, with the fulcrum F' at the middle, so that when a swinging motion is given to the levers they move the friction-disks D in engagement with the friction-disks B, while the pinions H are thrown out of mesh with the gear-wheels C. A reverse swinging motion given to the levers F moves the pinions H in mesh with the gear-wheels C and carries the friction-disks D out of engagement with the friction-disks B.

On the shaft E is formed a crank-arm E',

connected by a pitman E² with the piston-rod of an air-compressor I, of any approved construction and secured to the under side of the vehicle-body, the said air-compressor discharging the air into a reservoir J, likewise attached to the under side of the vehicle-body. The other shaft G, carrying the pinions H, is formed or provided with a crank-arm G', connected by a pitman G² with the piston-rod of an air-motor K, secured to the under side of the vehicle-body and deriving its motive agent by a pipe K' from the reservoir J.

In order to impart a swinging motion to the levers F, I connect the lower end thereof by a link L with a hand-lever N under the control of the operator seated on the vehicle-seat. The levers F are also connected by a link L' with a brake-lever L², connected by a link L³ with the hand-lever N, as indicated in Fig. 1. By thus connecting the swinging levers F with the operating-lever N the fulcrum of the said levers is relieved of strain, and as the links alternately pull and push I am enabled to use very light links.

It will be seen that the operator by manipulating the hand-lever N can readily impart a swinging motion to the levers F, so that the disks D are thrown in engagement with the friction-disks B during the time the vehicle is going downhill, so that the air-compressor I is actuated to fill the reservoir J with compressed air and at the same time acts as a brake on the vehicle to check its downward movement.

In the pipe K' is arranged a valve O, having its valve-stem provided with arms O', connected by links O² with an arm O³, fulcrumed on the front end of the vehicle-body and connected by a link O⁴ with a foot-lever O⁵ under the control of the operator. Thus when the vehicle reaches the bottom of the grade the operator imparts a swinging motion to the levers F by manipulating the hand-lever N so that the disks D are moved out of engagement with the disks B. The operator by imparting further movement to the levers F can throw the pinions H in mesh with the gear-wheels C, and by manipulating the foot-lever O⁵ can open the valve O, so that compressed air previously stored in the reservoir J can flow from the latter to the air-motor K,

so as to actuate the same, and consequently 65
rotate, by the pinions H, the gear-wheels C
and the axle A' to propel the vehicle. The
hand-lever N and the levers F are so arranged
5 that the disks D and pinions H can be thrown
into an intermediate position—that is, out of
contact with the disks B and gear-wheels C.

As illustrated in Fig. 3, the motor K is
connected at its supply-pipe K' with a pipe
10 K², opening into the ends of the cylinder, to
supply the latter with compressed air, using
the pipe K² for the exhaust-pipe. For this
purpose I provide the valves K³ K⁴ K⁵, of
15 which the valve K³ serves to open and close
the pipe K', and the valve K⁴ serves to con-
trol the inlet and outlet of the air at one end
of the cylinder, and the other valve K⁵ con-
trols the inlet and exhaust of air at the other
20 end of the cylinder. The several valves are
provided with arms K⁶, connected with each
other by links K⁷, and one of the arms is
connected with a slotted link P, pivoted on a
rod P', extending from the cross-head P² of
25 the motor.

It is evident that when the motor is running
30 the cross-head P² and rod P' carry the
slotted link P forward and backward, so as
to open and close the valves K³ K⁴ K⁵ simultaneously
35 for admitting compressed air alternately
to the ends of the cylinder and to exhaust
the air therefrom.

Having thus fully described my invention,
I claim as new and desire to secure by Letters Patent—

35 1. A motor for vehicles, comprising an air-
compressor, a reservoir for the compressed air,
an air-motor connected with the said reservoir,
swinging wheels adapted to be alternately thrown
40 into engagement with wheels on the axle of the vehicle,
a connection between one of the swinging wheels and reservoir,
and a connection between the other wheel and the motor, substantially as and for
the purpose set forth.

45 2. A vehicle-motor, comprising gear-wheels
and friction-disks on the axle of the vehicle,
gear-pinions and friction-disks adapted to be
thrown in engagement with the said friction-
disks and gear-wheels, levers carrying the
50 shafts for the said friction-disks and gear-
pinions, an air-compressor actuated from the
friction-disks, a reservoir adapted to receive
the compressed air from the compressor, and
an air-motor connected with the shaft of the
55 gear-pinions, substantially as shown and de-
scribed.

3. A vehicle-motor, comprising gear-wheels
and friction-disks on the axle of the vehicle,
gear-pinions and friction-disks adapted to be
60 thrown in engagement with the said friction-
disks and gear-wheels, levers carrying the
shafts for the said friction-disks and gear-
pinions, an air-compressor actuated from the
friction-disks, a reservoir adapted to receive

the compressed air from the compressor, an 65
air-motor connected with the shaft of the
gear-pinions, and means, substantially as de-
scribed, for controlling the said levers, as set
forth.

4. The combination with a vehicle provided 70
with friction-disks and gear-wheels on its
axle, of levers fulcrumed at about the center
of their length, crank-shafts mounted in op-
posite ends of the levers, friction-disks on
75 one of the shafts, pinions on the other shaft,
an air-compressor having its piston connected
with the crank of the shaft carrying the fric-
tion-disks, a reservoir adapted to receive air
from the compressor, and an air-motor con-
80 nected with the crank of the shaft carrying
the pinion and connected with the reservoir,
substantially as described.

5. The combination with a vehicle having
friction-disks and gear-wheels on its axle, of
85 swinging friction-disks and pinions adapted
to be alternately thrown into engagement
with the disks and gear-wheels on the axle,
an air-compressor having its piston connected
with the swinging friction-disk to be oper-
90 ated thereby, a reservoir with which the com-
pressor is connected, a motor having its pis-
ton connected with the swinging pinion, a
pipe connecting the motor with the reservoir,
and a valve in said pipe and under the control
95 of the operator, substantially as described.

6. The combination with a vehicle having
friction-disks and gear-wheels on its axle, of
centrally-pivoted levers, crank-shafts mounted
100 in the ends of the levers, disks on one
shaft, pinions on the other shaft, a reservoir,
a compressor connected with the reservoir and
having its piston connected with the shaft of
the disks, a motor connected with the reservoir
105 and having its piston connected with the
shaft of the pinions, the brake-lever, a link
connecting one end of the lever with the said
swinging lever, an operating-lever, and a link
connecting the other end of the brake-lever
110 with the operating-lever, substantially as de-
scribed.

7. A motor for vehicles, comprising gear-
wheels and friction-disks on the axle of the vehicle,
pivoted levers, friction-wheels carried
115 at one end of the levers, pinions at the other
end of the said levers, a reservoir, an air-com-
pressor connected with the shaft of the fric-
tion-wheels, an air-motor connected with the
shaft of the pinions, a connection between the
120 motor and reservoir, a valve in said connec-
tion, means for operating the valve, and means
for swinging the levers carrying the friction-
wheels and pinions, substantially as herein
shown and described.
